UNITED STATES PATENT OFFICE.

JULES A. PERRAULT, OF LOWELL, MASSACHUSETTS, AND HENRY LUBÉ, OF ASTORIA, NEW YORK, ASSIGNORS TO RECREATOR PHONOGRAPH CORPORATION, OF BOSTON, MASSACHUSETTS, A CORPORATION OF MASSACHUSETTS.

PROJECTING APPARATUS.

Application filed December 17, 1921. Serial No. 523,185.

This invention relates to projecting apparatus and the object of the invention is to provide a motion picture projecting apparatus for projecting films of the type disclosed in our application filed December 17, 1921, Serial Number 523,184.

In the said application is disclosed and claimed an endless film having pictures printed thereon in a plurality of adjacent rows separated by perforations.

The apparatus according to this invention is designed to project said film by providing suitable mechanism engaging said perforations to operate the film past suitable projecting lenses.

In the drawing accompanying this specification,

Fig. 1 is a vertical central sectional view of a motion picture apparatus showing the casing, film driving and projecting means as well as the electric light and other details.

Fig. 2 is a sectional view of the motion picture apparatus taken on line 2—2 of Figure 1.

Fig. 3 is a similar view taken on line 3—3 of Figure 1.

Fig. 4 is a sectional detail view of the means for keeping that position of the film which is being projected in proper relation to the projecting lenses.

Fig. 5 is a diagrammatic view illustrating the film.

Referring to Figure 5 the reference numeral 10 denotes an endless film provided with rows of pictures 11 separated by rows of perforations 12. The joined ends of the film 13 and 14 are off-set with respect to each other so that when the film is operated, as by suitable sprocket wheels engaging the said perforations, the pictures will be operated in succession past a given point for projection purposes. The construction of the film and the arrangement of the pictures and perforations are fully disclosed in the application referred to.

Referring to the drawings the numeral 25 denotes a suitable bracket or base for the support of the machine and which bracket may be secured to a cabinet or

stand represented by a wall or portion 26. 50 A partition 27 is adapted to cover the base 25 to form a grease chamber 28 within the base, which is circular as shown in Figure 3.

The projecting mechanism is contained with a cylindrical hollow casing 29 which 55 is secured to the base by screws 30. The end of the casing is closed by a cover 31. Suitably journaled in a bearing 32 and in the partition 27 is the operating shaft 24 which carries a plurality of sprocket wheels 60 23, 28 properly spaced on the shaft by sleeves 33. Each wheel has a key 34 which fits in a key-way 35 in the shaft 24 whereby all the sprocket wheels are properly aligned. As seen in Figures 2 and 3, the casing 29 65 is cut out opposite each wheel to form an opening 36 through which the teeth on the wheels project.

A suitable illuminating means such as an electric lamp 37 is provided in the casing 70 and may be focussed or adjusted with respect to the projecting means, i. e., lenses 22. As shown, the lamp may be mounted in a base 38 frictionally fitted within a flange 39 for purposes of adjustment. The 75 casing is provided with a projecting opening 40, see Figure 2, and inside the casing and in line with said opening there are provided suitable light concentrating lenses 41, 41 in a housing 42. A shutter 43 is carried 80 by a shaft 44 journaled in a bracket 45. The shutter shaft is driven from the shutter operating shaft 46 by bevel gears 47. The shaft 46 is journaled in the bracket 45 and the aforesaid partition 27 as shown. 85

The film operating shaft 24 is driven intermittently from the driving shaft 48 located in the bracket 25 by means of a Geneva stop movement mechanism comprising the slotted disk 49 fast on the said shaft 90 24 and operated by the pin 50 in the driving gear 51, while 52 indicates the usual stop cam. The driving gear 51 is fast on the driving shaft 48 which carries a fly wheel 53 to regulate the speed. A connection 54 95 may be used to connect the driving shaft to a source of power. The shutter operating shaft 46 carries a gear 55 which meshes

with an idler gear 56 driven from the driving gear 51. The gears and the Geneva stop movement are all contained within the grease chamber 28, which may be filled with grease to render the operation noiseless.

The reference numeral 60 denotes a cover, which extends the length of the casing 29 and is semi-cylindrical or curved in cross section. The cover is hinged to the bracket 10 25 by means of lugs 61 and pivots 62. The free end of the cover rests upon the end cover 31 of the casing. A handle 63 is provided for lifting the cover and swinging it about its pivots 62 aforesaid. The cover 15 carries the projecting means 22 comprising suitable lenses 64 in an adjustable housing 65. The cover further carries a "framing" member 66 which is in the form of a strip of thin metal, see Figures 2 and 4, which 20 is secured to the cover by springs 67 held by screws or rivets 68 and provided with an opening 69.

In operating the projection apparatus, the cover is lifted and swung about its pivots 25 62, thus exposing the top of the casing 29 and the sprocket wheels 23 through the openings 36. The operator then takes the film and places it around and upon the casing by slipping the film endwise in over the 30 casing. The first picture is placed in register with the projection opening 40, and as the film hangs down over the casing the perforations 14 naturally engage some of the sprocket wheels. Looking at Figure 1, 35 the film will thus engage the four wheels 23 situated to the right of the lamp 37. Next to the cover is lowered until it rests upon the casing cover 31 whereby there is formed a narrow semi-cylindrical chamber or passage 40 70 extending the length of the casing. In closing down the cover the "framing" member 66 is brought into yielding engagement with the film to both sides of the projecting means and as the film passes around 45 the casing, said framing member by keeping it in close contact with the casing, prevents slipping or displacement of the film and "frames" the pictures correctly. The 50 opening 69 in the framing member registers of course with the opening 40 in the casing 29.

The machine is then started by applying power to the driving shaft 54 whereby the film, through the instrumentality of the 55 sprocket wheels 23 will be operated intermittently in the usual manner and the pictures will be successively projected as will be understood. During this operation the film will be rotated around the casing 29 and will 60 also be moved axially thereof, or in other words, the film will be moved spirally

around the casing until all the pictures have been projected.

The apparatus as herein disclosed is very simple in construction and may be produced 65 at a low cost. It is particularly well adapted for shipping or carrying about.

It will be understood that the construction set forth is illustrative and may be altered and changed without departing from the 70 principle of the invention or the scope of the appended claims.

We claim:

1. A motion picture apparatus comprising a cylindrical casing, a cover therefor, 75 co-operating film projecting means carried by said casing and cover, and means for operating a motion picture film between said casing and cover to cause the film to be projected by the said co-operating film project- 80 ing means.

2. A motion picture apparatus comprising a cylindrical casing, a cover therefor hinged at the one end of said casing, which latter is arranged to receive an endless motion picture film lengthwise thereof, said film being adapted to rest upon the said casing beneath the said cover, co-operating projection means carried by said casing and cover, means for registering the film with 85 respect to said projection means and means within said casing, but projecting therefrom, for operating said film past the said projection means to cause said film to be 90 projected. 95

3. A motion picture apparatus comprising a cylindrical casing, a cover therefor hinged at the one end of said casing, which latter is arranged to receive and support upon its top curved surface an endless motion picture film lengthwise thereof, said film being adapted to rest upon the said casing beneath the said cover, cooperating projection means carried by said casing and cover, means for 100 registering the film with respect to said projection means and means within said casing, but projecting therefrom and engaging the film for moving the same both lengthwise and sidewise, for operating said film past the said projection means to cause said film 105 to be projected. 110

4. In a moving picture apparatus the combination of a drive shaft, a film operating shaft intermittently driven therefrom and carrying a series of sprocket wheels, a shutter operating shaft parallel to the sprocket shaft, a driving gear between said drive shaft and said shutter operating shaft and a vertical shaft geared with the shutter operating shaft and carrying the shutter. 115
